(57) **CLAIM**

The ornamental design for a portable pool kit, as shown and described.

DESCRIPTION

FIG. 1 is a perspective view of a portable pool kit of the invention with the components gathered together in the bucket;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of a portable pool kit of the invention displaying kit components;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a perspective view of a portable pool kit of the invention displaying the kit in use;

FIG. 16 is a cross-sectional view taken on line 16—16 of FIG. 15; and,

FIG. 17 is a top plan view thereof.
